ABSTRACT: A machine for sharpening each one of the symmetrical portions of a drill point as a conical central surface portion edged with a part-spherical surface portion tangent to the central portion including a rotatable drill holder mounted on a bent arm with the arm pivotally mounted about an oblique axis to the plane of a grinding wheel.

MACHINE FOR SHARPENING TWIST DRILLS

This is a division of application Ser. No. 646,254, now U.S. Pat. No. 3,535,831 issued Oct. 27, 1970, filed June 15, 1967, relating to a new method of sharpening twist drills. The present invention relates to a new machine for sharpening twist drills according to the aforesaid method.

Drilling is a very frequent operation in industry and therefore it is advantageous to make it as economical as possible. This invention provides a twist drill sharpening machine whereby twist drills can be operated at higher speeds, thus reducing drilling time, with a method imparting a greater resistance to drill wear, thereby making resharpening operations less frequent and permitting drilling a greater number of holes with the same drill, so as to reduce the holdup time of the drilling machine or other machine on which twist drills are used. Moreover, the holes are more accurate to size and better finished.

The present invention relates to a machine for sharpening twist drills, adapted to form each one of the symmetrical surface portions of the drill point as a conical central surface portion edged with a part-spherical or toroidal surface portion tangent to said central surface portion, which comprises a grinding wheel and a depending bent arm supporting a drill holder and pivotally mounted about an axis other than the geometrical axis of the drill in order to sharpen as usual the conical portion of the drill point against the plane of the grinding wheel, said drill holder being rotatably mounted about an axis perpendicular to said pivot axis and forming the center of rotation for obtaining said part-spherical surface portion, said drill holder comprising a drill-clamping device rotatably mounted about the geometrical axis of the drill and means being interposed between said drill-clamping device and said bent arm in order to produce the rotation of said drill about its axis in conjunction with the rotation of said drill holder with a view to obtain said part-spherical surface.

The advantageous features resulting from this invention will appear more clearly as the following description of such a machine proceeds with reference to the accompanying drawings, the description making at first a comparison between the known methods and the method carried out by the machine according to the invention.

In the drawings:

FIG. 1 is a side elevational view of the tip of a conventional twist drill;

FIG. 2 is a diagram for explaining the manner in which the twist drill of this invention is sharpened;

FIG. 3 is a view of the tip of a twist drill sharpened according to the known method forming superposed tapered annular surface portions;

FIG. 4 is a diagram for explaining the cone-and-sphere sharpening method which may be carried out by the machine of this invention;

FIG. 5 is a diagram for explaining the cone-and-tore sharpening method which may be carried out by the machine of this invention, and

FIG. 6 is a perspective view of the machine.

Referring first to FIG. 1, there is shown therein a conventional twist drill of which the point consists of two tapered surfaces such as 1 separated by helical grooves 2, the cutting edges being designated by the reference numeral 3.

A twist drill of this conventional type is usually sharpened as shown in FIG. 2. The apparent vertex angle of the drill being Φ , the two conical surfaces 1 are obtained as the rake, in relation to the cutting edges 3, by rotating the drill about an axis Δ inclined by an angle β in relation to the plane of the grinding wheel 4, the axis converging to a point S located on this plane.

On the other hand, assuming that said axis Δ lies in the horizontal plane of the figure, in most cases, the drill axis XY is located in another horizontal plane disposed slightly below the preceding one.

The vertex S of the sharpening cone and the angle 2β of this cone are generally fixed and characteristic of a sharpening machine.

Experience teaches that this conventional sharpening method is not completely satisfactory.

In fact, the cutting edges 3 wear out rapidly in their outer peripheral portion (as shown by the shaded area 5 of FIGS. 1 and 2) because they operate under detrimental conditions since the cutting speed increases from the center of the drill to the periphery thereof, and also because the actual rake, in contrast thereto, decreases from the center to the periphery.

Under these conditions, the rapid wear of the twist drill in said areas 5 will rapidly affect the quality of the drilling and lead to serious damages in the drill tip, so that the drill must be withdrawn from actual service to avoid its complete destruction.

It is known to endeavor to reduce the consequences of this defect by having each symmetrical surface portion of the drill point made not of a single conical surface but of a plurality of superposed conical or frustoconical surfaces 1, 6 and 7 having decreasing vertex angles Φ , Φ_1 , Φ_2 from the point outwards. Now this method is not fully satisfactory for in addition to the considerable time necessary for properly performing the sharpening operation the resulting angles still wear out at an abnormally high rate.

With the method of sharpening twist drills which may be carried out by the machine according to this invention the various inconveniences set forth hereinabove are safely avoided by forming notably each one of said symmetrical surface portions of the drill point as a conical surface at the center which merges into a part-spherical or toroidal peripheral surface (FIG. 4) tangent to said conical surface.

In the first case, as shown in FIG. 4, the two symmetric surface portions of the drill tip consist each of a conical portion 8 surrounded by a part-spherical surface portion 9, the relative surface area of these portions being variable to a substantial extent.

The part-spherical portion 9 is centered at M lying on the axis Δ of the sharpening cone and a radius R such that the sphere centered at M is tangent to the conical portion 8. The point M is projected at M_1 on the drill axis XY which, as already explained, is still positioned in a horizontal plane underlying the plane of the figure.

In the second case (see FIG. 5) the conical portion defined hereinabove merges tangentially to a toroidal surface 10 pertaining to a tore having a radius r smaller than R, inscribed in the sharpening cone.

Thus a considerably more satisfactory rake can be obtained along the cutting edges in comparison with the conventional method.

In fact, if we consider the conical surface portion 8 we see that the rake is effectively obtained, as in the conventional sharpening method, by rotating the drill about the axis Δ inclined by the angle β in relation to the plane of the grinding wheel 4 and passing through the point S spaced by a distance OS from the drill point, but the fact that the cutting edge corresponding to this conical surface portion does not extend beyond the point A and is therefore shorter than the drill diameter causes the real rake to vary within narrower limits and preserves an acceptable value at A. Moreover, with this method the values of β and OS are not fixed and can easily be selected as a function of the characteristics and conditions of use of the twist drill (diameter, vertex angle, material to be drilled, cutting speed, feed, etc.) so that the most satisfactory rake value can be applied.

Reverting now to FIG. 4, and considering the part-spherical portion 9, a satisfactory rake of cutting edges AC and BD is obtained according to the present invention not only by shifting the twist drill vertically and rotating it about the axis Δ as in the preceding case, but also by simultaneously rotating the drill about the vertical axis MM₁ and its axis XY in order to obtain along the entire cutting edge an optimum real rake, with due consideration for the operating conditions of the twist drill and for its inherent characteristics.

The method of sharpening twist drills having a conical and toroidal point as shown in FIG. 5 is similar to that of the twist drill having a conical and spherical point as shown in FIG. 4, except that it is the grinding wheel that is rotated for generating the elementary toroidal surfaces and that the drill is not rotated about its axis.

The machine illustrated in FIG. 6 permits making all the sharpening operations necessary for carrying out the above disclosed and defined method.

This machine comprises a bent arm 11 mounted for rotation on a supporting frame 12 about an axis corresponding to the aforesaid axis Δ , and adapted to rotate through a certain angle about this axis. The arm 11 carries through the medium of a member 11a rigid therewith a drill holder 13 of which the axis XY, in its initial vertical position, intersects the axis Δ at the point M and forms therewith the angle γ indicated on FIGS. 4 and 5. The drill holder 13 comprises a support 13a rotatably mounted on member 11a about a vertical axis shown geometrically at MP which is perpendicular at M to the horizontal plane containing the axes Δ and XY. Said drill holder comprises an inner jaw chuck 14 in which the twist drill can be locked in a predetermined initial position.

The chuck proper is adapted to be rotatably driven from a toothed wheel rigid therewith, disposed in a case 15 and meshing with a rack 16 slidably mounted on the drill holder, the movements of this rack being controlled through a roller 17 rigid with said rack and a cam 18 mounted on the member 11a of arm 11; in other words, when the drill holder 13 is rotated about the axis MP the twist drill is rotated simultaneously about its axis XY. The rotation of the drill holder 13 about the axis MP is controlled in this case through a transmission (not shown) connecting same within the arm 11 to a handwheel 19 mounted thereon in the vicinity of the pivot corresponding to the axis Δ . The rotation of arm 11 about this axis is controlled by means of a handwheel 20 mounted on the frame 12.

This machine further comprises a grinding wheel 4 rotatably mounted on a bearing block 22 slidably mounted in turn on and vertically adjustable in relation to, a bracket 23 adapted to slide horizontally in two directions at right angles to each other in relation to a support 24, due to the interposition of a plate 25 on which said bracket is adapted to slide in one of these two directions, this plate 25 being adapted in turn to slide on the support 24 in the other direction perpendicular to the preceding one.

The support 24 is pivoted on a sector 26 about an axis TU initially in alignment with axis MP and adapted to be shifted so as to remain parallel thereto by a sliding mounting of sector 26, in two perpendicular directions obtained respectively between the sector 26 and a plate 27, and between this plate 27 and a base plate 28. This base plate 28 is pivoted in turn about an axis SV also in alignment with the uppermost axis MP.

The drill holder 13 is adjustable in the vertical direction by means of its support 13a in order to provide the shift MM₁ mentioned hereinabove.

Thus, with this machine, the part-spherical portion of the drill tip is sharpened by keeping the axis TU in alignment with the vertical axis MP, the toroidal surface portion being sharpened by shifting these axes, that is, members 26 and 28, in relation to each other. In this last case, it is the grinding wheel that will be gradually turned about the axis TU to generate the elementary toroidal surfaces. A driving mechanism (not shown) of any suitable and known type is interposed to this end between the members 24 and 26.

For example, the sharpening of one of the symmetrical surface portions of a drill point with a part-toroidal surface portion as shown in FIG. 5, includes the following steps:

Setting all of adjusting means of the machine to zero;

Pivoting the base plate 28 around the axis SV and clamping it at the desired angle β (beta);

Positioning the axis TU in alignment with the origin point of radius r , this positioning resulting from a given shifting of the sector 26 relative to the plate 27 and of the latter relative to the baseplate 28, that is a resultant given shift relative to the aligned axis SV and MP;

Adjusting the supports 23 and 25 to place the grinding wheel plane at a distance r from the axis TU;

Orienting the axis XY of the drill holder 13 according to the given angle γ , by rotating its support 13a relative to the member 11a;

Adjusting the height of the axis XY of the drill holder 13 on its support 13a, to provide the shift MM₁ aforementioned;

Mounting the drill in the drill holder including placing of the cutting edge to be sharpened in the grinding wheel plane; Generating the conical portion OA of the drill point by an oscillating rotation of the arm 11 and drill holder 13 around the axis MS, by means of handwheel control 20;

Generating the toroidal surface AE by an oscillating rotation similar to the preceding one, combined with a rotation of the grinding wheel support 24 around the axis TU, relative to the sector 26.

The sharpening of one of the symmetrical surface portions of a drill point with a part-spherical portion as shown in FIG. 4, includes the following steps:

Setting of all adjusting means of the machine to zero; Pivoting the base plate 28 around the axis SV and clamping it at the desired angle β .

Adjusting the supports 23 and 25 to place the grinding wheel plane at a distance R from the axis MPTU;

Orienting the axis XY of the drill holder 13 according to the given angle γ ;

Adjusting the height of the axis XY of the drill holder on its support 13a to provide the shift MM₁;

Mounting the drill in the drill holder including placing of the cutting edge to be sharpened in the grinding wheel plane;

Generating the conical portion OA of the drill point by an oscillating rotation of the arm 11 and drill holder 13 around the axis MS, by means of handwheel control 20; and

Generating the spherical surface by an oscillating rotation similar to the preceding one, combined with a rotation of the drill holder support 13a around the axis MP, by means of handwheel control 19.

It may be added that the machine described hereinabove further permits, in addition to the sharpening of twist drills, for which it was specially designed, other special sharpening works, and notably of obtaining the perfect joining of the lateral surfaces of a cutting tool (for lathe, planing-machine, etc.) by means of conical surfaces, whatever the necessary rakes may be.

We claim:

1. A machine for sharpening twist drills adapted to form each one of the symmetrical surface portions of the drill point as a conical central surface portion edged with a part-spherical or toroidal surface portion tangent to said central surface portion, which machine comprises a grinding wheel, a support frame, a bent arm having a drill holder on one end thereof, said bent arm being pivotally mounted by its other end on said support frame for movement about a pivot axis oblique to the plane of the grinding wheel and to the longitudinal axis of a drill in said drill holder in order to sharpen the conical portion of the drill point against the grinding wheel, said drill holder being mounted on said bent arm for rotation about an axis perpendicular to said pivot axis and forming the center of rotation for obtaining said part-spherical surface portion, said drill holder comprising a drill-clamping device mounted for rotation about the longitudinal axis of the drill and means interposed between said drill-clamping device and said bent arm to produce rotation of said drill about its axis in conjunction with the rotation of said drill holder to obtain said part-spherical surface.

2. A machine according to claim 1, wherein said means interposed between said drill-clamping device and said bent arm comprises a pinion carried by said clamping device, a rack meshing with said pinion and slidably mounted on a drill holder support and a cam rigid with said bent arm.

3. A machine according to claim 2, further comprising support means having said grinding wheel mounted thereon for three-dimensional adjustment, a plate having said support means mounted thereon for pivotal angular movement about an axis adapted to be shifted in parallel relation to the axis of

rotation of the drill holder to thereby generate one of said part-spherical and toroidal surface portions.
